(57) CLAIM

I claim the ornamental design for a handbag with ornament, as shown and described.

DESCRIPTION

FIG. 1 is a perspective view of a handbag according to the present invention.

FIG. 2 is a front view of the handbag of FIG. 1.

FIG. 3 is a rear view of the handbag of FIG. 1.

FIG. 4 is a left side view of the handbag of FIG. 1.

FIG. 5 is a right side view of the handbag of FIG. 1.

FIG. 6 is a top view of the handbag of FIG. 1.

FIG. 7 is a bottom view of the handbag of FIG. 1.

FIG. 8 is a perspective view of a second embodiment of a handbag according to the present invention.

FIG. 9 is a front view of the handbag of FIG. 8.

FIG. 10 is a rear view of the handbag of FIG. 8.

FIG. 11 is a left side view of the handbag of FIG. 8.

FIG. 12 is a right side view of the handbag of FIG. 8.

FIG. 13 is a top view of the handbag of FIG. 8; and,

FIG. 14 is a bottom view of the handbag of FIG. 8.

The broken lines showing the handbag handle are for the purposes of illustrating environment and forms no part of the claimed design.
